UNITED STATES PATENT OFFICE.

WILLIAM H. BATES, OF CHICAGO, ILLINOIS.

VALVE-OPERATING MECHANISM FOR STEAM-ENGINES.

1,120,994.

Specification of Letters Patent. Patented Dec. 15, 1914.

Application filed December 11, 1911. Serial No. 665,089.

To all whom it may concern:

Be it known that I, WILLIAM H. BATES, a citizen of the United States, residing at Chicago, in the county of Cook and State of Illinois, have invented certain new and useful Improvements in Valve-Operating Mechanism for Steam-Engines, of which the following is a description.

My invention belongs to that general class 10 of devices known as steam engines or the like, and relates particularly to an improved centralized valve gear or operating mechanism.

The device is particularly intended for 15 use on horizontal marine engines, wherein the crank shaft is usually placed at some distance from the cross-head, and a comparatively long connecting rod employed. With engines of this type the eccentric rod 20 for operating the valve mechanism ordinarily extends to the crank shaft. With my improved construction only the connecting rod extends to the crank shaft, and a comparatively short rod for operating the valve 25 mechanism is employed, the usual eccentric rods, cams and links being eliminated.

The present invention is also an improvement over the engine shown in Letters Patent of the United States No. 738,147, dated 30 September 8, 1903, issued to myself and Robert C. Douglas for a variable cut-off for steam engines, and includes an improved mechanism for operating the rod, which operates the supplemental valve mechanism.

35 My invention also has further among its objects the production of an engine of the kind described that is simple, durable, compact, efficient and satisfactory.

The invention is particularly suitable for 40 horizontal long stroke marine engines of the type shown and described, but its use, however, is not confined to such engines, as it may be used wherever found applicable.

To this end my invention consists in the 45 novel construction, arrangement and combination of parts herein shown and described, and more clearly pointed out in the claims.

In the drawings, wherein like reference 50 characters indicate like or corresponding parts, Figure 1 is a top plan view of a portion of the engine, showing the cross-head and guides therefor, and my improved main and supplemental valve operating mechanism. Fig. 2 is a side elevation of one side 55 of the engine, showing a portion of the

mechanism for operating the main valve. Fig. 3 is a side elevation of the opposite side of the same, showing the mechanism for operating the supplemental valve mechanism. Fig. 4 is a sectional view taken substantially on line 4, 4 of Fig. 2, and Fig. 5 is a side elevation of the engine cylinder of a horizontal marine engine, showing a portion of the variable cut-off mechanism similar to that described in the patent previously mentioned.

Referring to the drawings, it may be mentioned, in order that the device may be more clearly understood, that Fig. 5 is substantially a continuation of Fig. 3 from line *a*, *a*, and that only a portion of the connecting rod 6 is shown, the remainder of the connecting rod, the crank shaft, etc., being omitted from the drawings, as the same is 70 preferably the usual and well known construction. The type of engine illustrated is 75 similar to that described in the patent previously mentioned, and consists of a suitable frame or bed 1, upon which is mounted a cylinder 2, from which is extended the right piston rod 3, which is connected with the cross-head 4 arranged to slide upon the cross-head guides 5. It is also unnecessary to go 80 into details as to the particular construction 85 of the valve mechanism other than to say that the main valve is operated by the valve stem 10, and the supplemental valves, which afford an adjustable variable cut-off, are operated by the rod 11, connected to a plate 12 90 pivotally mounted on a shaft 13, the supplemental valve mechanism being operated by the rod 11, and the regulation being controlled as described in the above mentioned 95 patent.

As previously mentioned, in the present construction the eccentric rods to the crank shaft, cams, etc., usually employed, are omitted. In place of the eccentric rod I arrange a rod 15, preferably in proximity to the cross-head guides 5, and extending along the same. The rod 15 is pivotally secured at one end at 16 to an arm 17, which is pivotally carried by a shaft or pin 19, carried by the bearing bracket 20. The opposite end of the rod 15 is pivotally secured at 22 to an arm 21, which is pivotally carried by a pin 25, supported by the bearing bracket 24. In the preferred construction, I provide arms 18 and 26, which form substantially bell cranks with the arms 17 and 21 and connect the free ends of the arms 18 and 100 105 110

26 by a rod 28 pivotally secured to the arms 27 and 29.

To one of the shafts or pins 25 or 19, preferably to the shaft 25, I secure an arm 31. The arm 31 is pivotally connected at 33 to a rod 32, which is preferably connected by a suitable reversing gear to the stem 10. The type of reversing gear shown is well known and comprises a saw-buck 35, having its central portion arranged between two pins 38 and 39, carried by a part 37 on a rotatable rock shaft 36. To maintain the parts in position, the plate or bar 40 (see Fig. 4) is preferably arranged at the ends of the bolts 38 and 39. The vertical position or adjustment of the saw-buck 35 is controlled by a rod 45 extending therefrom, which may be raised or lowered by a rod 46, so that as the rod 46 is raised or lowered, the saw-buck 20 part 35 is raised or lowered to engage the upper pin 38, or the lower pin 39, as may be desired. Shifting the parts as described of course changes the direction of rocking of shaft 36 relative to the travel of the piston. 25 The regular shaft 36 is preferably extended upwardly to form a bracket 47. A rod 48 is pivotally connected at 49 (see Fig. 4) the rod 48 being suitably connected to the main valve rod 10 (see Figs. 1 and 5). 30 Secured to the connecting rod 6, is a bracket 51, which carries a part 52 pivotally secured to the bracket at 53, the part 52 being adapted to slide back and forth on the rod 15 as the connecting rod is operated. As 35 the engine is driven, the bracket 51 is reciprocated, drawing down the rod 15 over the guides at one end, as shown at the crank end, as the piston moves forward, and raising the opposite end as it is reciprocated 40 back toward the piston or cylinder. Drawing down and raising the ends of the rod 15 as the piston reciprocates back and forth, operates the valve rod 10, the movement of the bar or rod 15 being communicated 45 through the bell crank 21, shaft 25, arm 31 and rod 32, saw-buck 35, one of the pins on the bars 37, bar 37, rock shaft 36, arm 47, the connecting rod 48, thereby operating the main valve to perform its usual functions. 50 With this construction it is not necessary to extend a rod to the crank shaft (not shown). For this reason the engine is particularly applicable for marine use in driving stern propellers or wheels, where a long stroke engine with a long connecting rod is usually used. 55

The mechanism for operating the supplemental valve mechanism is substantially similar in construction, and comprises a rod 60 56 (see Figs. 1, 3 and 4) which is pivotally supported at 60 and 58 from the arms 59 and 57. The arm 57 is preferably loosely mounted upon the shaft 36, and is provided with an extending or bell crank arm 63, to 65 which is pivotally secured at 64 a supple-

mental valve operating rod 11. The arm 59 is pivotally supported at 61 from a bearing bracket 62, and is provided with an extending bell crank arm 65. The arm 63 and arm 65 are tied together by a rod 66, pivotally secured to the arms at 64 and 67 respectively.

Carried by the cross head 4 is an extended arm 68 provided with a bearing box or plate 69, which embraces the rod 66, the part 68 75 being preferably secured at 70 of the cross head. The operation of this mechanism is substantially similar to that previously described for operating the main valve. As the cross-head is reciprocated back and forth, the rod 56 is operated so as to operate or rock the arm 57, thereby rocking the arm 63 and operating the supplemental valve operating rod 11. Operating the rod 11 rocks the plate 12 (see Fig. 5) which, in turn, 85 controls the supplemental valve mechanism in the manner described in the patent previously mentioned.

It is, of course, understood that either one or both the mechanisms described for both 90 valve mechanisms may be employed, or that the same may be employed for operating only one of the mechanisms. I do not wish to be understood as limiting myself to the use of the construction embodying a variable 95 cut-off, inasmuch as the same may be used wherever found applicable; neither do I wish to be understood as limiting the use of the same to a horizontal marine engine 100 of the type mentioned. The advantages of this construction, particularly when applied to a horizontal marine engine of the type described, are many. Eccentric rods, cams, links, etc., are eliminated, removing the difficulty often experienced in the breaking of 105 these parts, especially on boats operated in shallow rivers or waters, where overhanging limbs of trees, etc., are liable to come in contact with the parts. The valve gear is in plain sight of the engineer and accessible 110 without going outside of the boat, and the room usually taken up on the crank shaft by eccentrics, cams and the like, allows just that much more space for the paddle wheels, so that longer lengths of paddle wheels may be 115 used.

Having thus described my invention, it is obvious that various immaterial modifications may be made in the same without departing from the spirit of my invention, 120 hence I do not wish to be understood as limiting myself to the exact form, construction, arrangement and combination of parts herein shown and described, or uses mentioned.

What I claim as new and desire to secure 125 by Letters Patent is:

1. In a valve operating mechanism, the combination with a valve and a reciprocating engine part, of valve gear including a longitudinally and transversely movable 130

bar disposed longitudinally with relation to the direction of movement of said reciprocating part, means for operatively connecting said bar with said reciprocating part 5 whereby said bar is actuated, and an operative connection between said bar and valve.

2. In a valve operating mechanism, the combination with a valve and a reciprocating engine part, of valve gear including a 10 longitudinally and transversely movable bar disposed longitudinally with relation to the direction of movement of said reciprocating part, means pivotally connected with the reciprocating part and slidably connected with 15 the bar to actuate the same, and an operative connection between said bar and valve.

3. The combination in a steam engine including valve mechanism, a reciprocating piston rod, cross head and connecting rod, 20 of a longitudinally and transversely movable bar disposed longitudinally with relation to said rods, supporting means for the bar comprising a pair of pivotally supported arms connected to the end of the bar, means 25 for connecting one of said arms to the valve mechanism, and means carried by the cross head and movable along the bar for actuating the same.

4. The combination in a steam engine including valve mechanism, a piston rod, cross head, and a connecting rod, of a longitudinally and transversely movable bar disposed longitudinally with relation to said rods, supporting means for said bar including a 30 plurality of pivotally supported arms, said arms being pivotally connected to said bar, means for pivotally and slidably connecting the bar with one of the reciprocating parts of the engine, said means comprising a member pivotally connected to one of said engine parts and slidably connected with said bar, and means for transmitting the movement of said bar to the valve mechanism.

5. The combination in a steam engine including valve mechanism, a reciprocating piston rod, cross head and connecting rod, of a longitudinally and transversely movable bar arranged substantially parallel with said rods, a pair of brackets carried by the bed 50 of the engine, a pair of arms pivotally carried by said brackets and pivotally connected at their free ends with the bar, one of said arms being provided with an arm extending therefrom and forming a bell crank, means for operatively connecting the last mentioned arm with the valve mechanism, and means operatively connecting the bar with one of the reciprocating parts of the engine.

60 6. A valve operating mechanism for steam engines comprising a horizontally inclined

longitudinally and transversely movable bar, an arm arranged at each end of the bar and pivotally secured thereto, means for pivotally supporting said arms, means for 65 connecting one of said arms with the valve mechanism, and a reciprocating part carried by one of the reciprocating parts of the engine, and slidable along the said bar to 70 actuate the same.

7. The combination with a steam engine including valve mechanism, a reciprocating piston rod, a cross head and connecting rod, of a horizontally inclined longitudinally and transversely movable bar disposed longitudinally with relation to said rods, means for supporting said bar, comprising a plurality of pivotally supported arms pivotally connected with the bar, one of said arms being 75 provided with a bell crank, and a connection 80 between said bell crank and the valve rod.

8. The combination of a steam engine provided with main and supplemental valve mechanisms, a reciprocating piston rod, cross head and connecting rod, of operating mechanism for said valves including a pair of longitudinally and transversely movable bars disposed longitudinally with relation to said rods, means for supporting said bars, means for connecting one of said bars to the main 85 valve mechanism, means for connecting the other bar to the supplemental valve mechanism, means connected with the engine connecting rod for operating one of the bars, and means connected with the engine cross 90 head for operating the other bar.

9. The combination with a steam engine including main and supplemental valve mechanisms, a reciprocating piston rod, cross head and connecting rod, of operating mechanism for said valves, including a pair of longitudinally and transversely movable bars disposed longitudinally with relation to said rods, means for supporting said bars, means for adjustably connecting one of said 100 bars to the main valve mechanism, means for adjustably connecting the other bar to the supplemental valve mechanism, means for operating said bars comprising a member pivotally secured to the connecting rod 105 of the engine and slidably mounted on the first mentioned bar, and a member pivotally connected with the engine cross head and slidably engaging the other bar.

In testimony whereof, I have hereunto 110 signed my name in the presence of two subscribing witnesses.

WILLIAM H. BATES.
